WINTERFRONT FOR MOTOR VEHICLES

Duerson Norvell Gatfield, Detroit, Mich.

Application August 5, 1938, Serial No. 223,171

18 Claims.

(Cl. 189—62)

My invention relates to shutters or winterfronts for radiators constituting a part of a cooling system for internal combustion engines employed for automotive purposes.

In the operation of tractors, trucks, and the like, using distillate and kerosene fuels, it is customary to employ gasoline or the like volatile fuel for starting purposes, since distillate and kerosene fuels are quite heavy and require more heat for proper vaporization than is available under ordinary starting conditions, particularly during periods of cool or cold weather. It is, therefore, highly desirable, when the engine is started, that it becomes heated quickly to the proper working temperature for use of the other and heavier fuel. It is also highly desirable that once the engine is brought to the proper heated condition and the heavier fuel cut in that the engine be maintained at or near a certain working temperature within a certain working range for most efficient utilization of the fuel.

Heretofore, it has been proposed to aid the foregoing conditions by the use of radiator shutters or winterfronts, but such prior devices have not fully served the intended purpose and are objectionable for several reasons. For example, it has been customary to employ winterfronts with overlapping shutter blades which have been so constructed that, when open, they materially obstruct the free flow of air to the radiator, thereby causing the engine to become overheated. Also, it is customary to employ a cooling fan behind the radiator for drawing air therethrough supplementary to the air passing through the radiator by virtue of movement of the vehicle. In the use of a fan, when the winterfront shutters are closed, a suction is created by the fan which tends to distort the shutter blades somewhat along their overlapping edges, thereby breaking the seal intended to be accomplished at that point, permitting cooling air to be drawn through the winterfront and radiator even when the winterfront is closed. This results in delayed heating of the engine, with consequent inconvenience in use of the tractor or other device, as well as increased fuel cost.

One of the objects of my invention is to provide a shutter or winterfront for tractors, trucks, and the like, by which all of the foregoing objectionable conditions are practically eliminated. More particularly, it is the principal object of my invention to provide an adjustable winterfront having shutter blades of such character that, when opened, they permit a free and practically unobstructed flow of air to the radiator, and

which, when closed, are tightly sealed against each other at and adjacent their overlapping edges.

Another object is to provide a winterfront of the foregoing character having shutter blades adapted to overlap in closed position, each shutter blade being provided with a plurality of suction slots by which the suction of the fan is employed to cause the overlapping shutter blades to seal against each other at the point of overlap.

Additional objects are to provide an improved mounting for winterfront shutter blades; and to provide a shutter or winterfront embodying the foregoing features which is of simple construction, is easy to manufacture, and which is adapted to perform its intended functions in a highly efficient manner.

Other objects and advantages will become apparent as this description progresses and by reference to the drawings wherein—

Figure 1 is a fragmental view of the front portion of a motor vehicle, such as a tractor, embodying my invention, the several parts being illustrated somewhat diagrammatically;

Fig. 2 is an enlarged rear elevational or inside view of one form of shutter or winterfront embodying my invention, such as illustrated in Fig. 1;

Fig. 3 is an enlarged, fragmental front elevational view, partially in section, of the upper portion of the structure shown in Fig. 2, the structure being shown in shutter-closed position;

Fig. 4 is a section taken substantially on line 4—4 of Fig. 3;

Fig. 5 is a fragmental section similar to Fig. 3 except showing the structure in shutter-open position;

Fig. 6 is a section taken substantially on line 6—6 of Fig. 4;

Fig. 7 is a fragmental cross-sectional view of a modified form of shutter structure that may be employed in carrying out my invention, the shutter blades being shown in closed position;

Fig. 8 is another fragmental sectional view of the shutter blades of Fig. 7, the same being shown in open position;

Fig. 9 is a cross-sectional view of another form of shutter blade that I may employ;

Fig. 10 is a fragmental, cross-sectional view of still another form of shutter structure that may be used in carrying out my invention, the structure being shown in full lines in closed position and in dotted lines in open position; and

Fig. 11 is a fragmental plan view of one of the shutter blades shown in Fig. 10.

Referring to Figs. 1 to 6, inclusive, a winterfront

20 embodying my invention is adapted to be mounted in front of a radiator 21 constituting a part of the cooling system for an internal combustion engine 22. The cooling system may further include a fan 23 of ordinary construction driven from the engine 22 through a fan belt 23^a in a conventional manner. The radiator 21 may take any suitable form arranged for the passage of air therethrough for the cooling of a liquid being circulated through the radiator. The engine 22 may take any desired form but, for the purposes of this description, it will be understood that it is of a type for use in tractors, trucks, and the like, and which is adapted for the use of distillate 5 or kerosene fuels. It is to be understood, however, that, while my invention will be described in its application to tractors, trucks, and the like, employing engines of the foregoing character, it is also well suited for use with any other automotive vehicle employing an internal combustion engine using any suitable fuel.

The winterfront 20 is secured in front of the radiator 21 by any suitable means including brackets 24 detachably connected at the side 25 thereof out of the path of the air passing through the winterfront 20 and the radiator 21. The winterfront 20 takes the form of a detachable unit which includes a rectangularly shaped frame formed of a plurality of strips 25. The frame strips 25 define an air passageway which is adapted to be opened and closed by a plurality of vertically disposed shutter blades 26. The frame strips 25 are of a width slightly greater than the width of the shutter blades 26 so that the latter may 30 be mounted within the frame and will be confined within the width limits of the frame in both the open and closed positions of such blades.

The shutter blades 26 are all of similar construction and only one will be described in detail. 40 Each shutter blade takes the form of a flat and comparatively narrow strip of sheet metal extending substantially throughout the height of the winterfront. One longitudinal edge of each shutter blade 26 is turned over to provide a comparatively narrow right-angled flange 27 thereat which strengthens the same sufficiently to prevent distortion of the shutter blade when it is moved about its pivotal support. Each shutter blade 26 is pivotally supported at its opposite ends so that 45 it moves with a hinge-like movement about a vertical axis. Specifically, at the opposite ends of the shutter blade, adjacent the side edge having the flange 27, I secure, by welding or otherwise, short swivel pins 28 (Figs. 3, 4 and 5), the outer ends of which project slightly beyond the ends of the shutter blade and rotatably engage in suitable openings provided in an internal frame-carried side member 29. A washer, or the like, 30 is mounted upon each of the pins 28 between the frame part 29 and the ends of the shutter blades so as to properly space the ends of the blades from the frame and to insure a free fit and rotary bearing which will not tend to rattle and become noisy.

60 All of the shutter blades 26 are mounted in the manner above described and they are interconnected through a common control means so that, upon actuation of the control means, they will all be moved simultaneously and to similar extent. 65 More particularly, at the upper end of each of the shutter blades 26, I provide a right-angled arm 31 (Figs. 3 and 6), which arm may be formed integral with the shutter blade or may be a separate strip welded thereto. Each of the arms 31 70 is connected by a swivel pin 32 to a laterally

shiftable control bar 33 located within the upper part of the frame. The control bar 33 is provided with an upstanding pin 34 which projects out through an arcuate slot 35 formed in the top side member 25 of the winterfront frame; and it 5 will be seen from the foregoing that by shifting the control bar 33 laterally all of the shutter blades 26 are moved to similar extents between open and closed positions. This movement is accomplished by a link 36 (Figs. 2 and 3), one end 10 of which is connected to the pin 34 and its other end is swingably connected at 37 to one arm of a crank member 38 supported at one side of the winterfront frame by a swivel pin 39. The other arm of the crank 38 supports a block 40 swiveled 15 therein and having a screw-threaded opening 41 which receives the outer and threaded end 42^a of a control rod 42. The other end of the control rod 42 is provided with a handle 43 which is located conveniently to the operator of the vehicle. 20 By rotating the handle 43 in one direction, the outer threaded end of such rod is screwed into the block 40, swinging the crank 38 rearwardly 25 of the winterfront and, in turn, moving the link 36 to the right (as viewed in Fig. 2) thereby moving the control bar 33 to swing the shutter blades 26 to an open position (Fig. 5). As the control rod handle is moved in opposite direction, the operating parts are returned to their normally closed position (Figs. 2 and 3) by a spring 44 30 mounted within the winterfront frame at the upper side thereof and having one end engaged with a pin 45 carried by the control bar 33 and its other end fastened to a frame-carried pin 46. In the use of the foregoing arrangement 35 the winterfront shutters 26 may be easily and quickly opened to any desired extent or closed, as operating conditions may require.

It is desirable, for reasons hereinabove stated, 40 that the shutter blades be fully sealed against each other when closed to prevent the passage of air therethrough and through the radiator 21 to the engine 22. To this end, I construct and arrange the shutter blades 26 in such a way that the suction established by the fan 23 is utilized 45 to tightly seal the overlapped portions of the blades against each other. More particularly, the shutter blades are of such width and are so arranged that, when closed, the free edge portion of one blade is disposed outwardly of and overlaps the flanged edge of the next adjacent shutter blade. Each shutter blade 26 (except the first one to the left as viewed from the front in Fig. 3) is provided adjacent its flanged edge 27 with a longitudinal row of spaced, comparatively narrow 50 and elongated slots 47. By arranging the shutter blades 26 as above described, the slots in each blade are disposed inwardly of the overlapping edge of the adjacent blade. In this way, each overlapping shutter blade is exposed to the suction of the fan 23 through the slots 47 in each overlapped blade; and, when the shutter blades 26 are fully closed and the fan 23 is in operation, 55 the suction created by the latter is effective through the slots 47 to draw the overlapping blade 60 surface tightly against the adjacent surface of the overlapped blade and substantially seal the same.

By reference to Fig. 5, it will be seen that, when 65 the shutter blades 26 are fully opened, as when 70 the engine is fully heated and it is desired to prevent overheating of the same, the flat, plane-surfaced blades offer but little obstruction to the free flow of air through the winterfront to the radiator 21. The only obstruction offered is by 75

the right-angled blade flanges 27 which are of slight height and offer a minimum restriction to air flow. To further minimize obstruction to air flow in the open position of the winterfront, the 5 free edges of the shutter blades are preferably rounded, as best shown in Fig. 6. If desired, a screen 63 of sufficient size to cover the forward part of the winterfront may be secured to the frame members 25, as shown in Fig. 3.

10 In some instances, dependent upon the length of the shutter blades and the particular material employed, it may be desirable to further strengthen the edge of the shutter blade that is connected to the frame to prevent sagging, buckling 15 or other distortion of the same. In that case, I may employ a shutter structure such as shown in Figs. 7 and 8, wherein each of the shutter blades 48 has its swiveled or pivoted edge rolled to provide a closed tubular reinforcing bead 20 49. The shutter blades 48 overlap each other, and that portion of the bead 49 of each blade which is overlapped is provided with a longitudinal series of spaced slots 50 similar to the slots 47 (Figs. 2 and 3). All of the blades 48 are pivotally supported similarly to the previously described blades 26 and their body portions are slightly offset at 48 so that the overlapping surfaces of the blades may seat flush against each other. Unless otherwise provided against, the 25 30 rolled or beaded blade edges 49 would tend to offer restriction to the flow of air through the winterfront when the shutter blades 48 are opened. To minimize such obstruction, the opposite sides of each bead 49 are provided with diametrically opposed, longitudinally extending rows of slots 51 which are disposed and aligned in a plane substantially parallel with the plane of the body of the shutter blades 48. In this way, when the blades 48 are opened, as illustrated in Fig. 8, the 35 40 slots 51 are then disposed substantially parallel with the path of air flow through the winterfront so that air may pass through the slots 51 with minimized restriction effect. When the shutter blades 48 are closed, the slots 51 also serve to 45 connect the overlapped slots 50 with the suction of the fan (such as the fan 23 of Fig. 1). In other words, the suction of the fan is effective at this time through the slots 50 and 51 to seal the overlapping portions of the blades 48 against 50 each other as in the first-described form. Also, 55 by locating the seal slots 50 in the beads 49, narrower shutter blades may be employed with less blade overlap, thereby tending to reduce the amount of blade material required as well as the 60 amount of space required for mounting and operating the blades. It will be understood, however, that, if desired, the slots 51 may be located in the plane body portion of the shutter blade closely adjacent to the bead 49 so that the suction of the fan is directly effective through the slots to seal 65 the shutter blades. In other respects, the shutter structure just described is similar to and operates like the structure previously described.

In some instances, I may employ a shutter 70 blade like that shown in Fig. 9. This shutter blade, which is designated by the numeral 52, is similar to that shown in Figs. 7 and 8 except that the bead 53 formed at the pivoted or swiveled edge of the blade is not completely closed, thereby 75 providing a continuous, open slot 54 along the inner side thereof. In this form, a longitudinal row of spaced slots 55 are provided in the head opposite the continuous slot 54 thereby tending to further minimize restriction to air flow through

the right-angled blade flanges 27 which are of slight height and offer a minimum restriction to air flow. To further minimize obstruction to air flow in the open position of the winterfront, the 5 free edges of the shutter blades are preferably rounded, as best shown in Fig. 6. If desired, a screen 63 of sufficient size to cover the forward part of the winterfront may be secured to the frame members 25, as shown in Fig. 3.

10 In some instances, dependent upon the length of the shutter blades and the particular material employed, it may be desirable to further strengthen the edge of the shutter blade that is connected to the frame to prevent sagging, buckling 15 or other distortion of the same. In that case, I may employ a shutter structure such as shown in Figs. 7 and 8, wherein each of the shutter blades 48 has its swiveled or pivoted edge rolled to provide a closed tubular reinforcing bead 20 49. The shutter blades 48 overlap each other, and that portion of the bead 49 of each blade which is overlapped is provided with a longitudinal series of spaced slots 50 similar to the slots 47 (Figs. 2 and 3). All of the blades 48 are pivotally supported similarly to the previously described blades 26 and their body portions are slightly offset at 48 so that the overlapping surfaces of the blades may seat flush against each other. Unless otherwise provided against, the 25 30 rolled or beaded blade edges 49 would tend to offer restriction to the flow of air through the winterfront when the shutter blades 48 are opened. To minimize such obstruction, the opposite sides of each bead 49 are provided with diametrically opposed, longitudinally extending rows of slots 51 which are disposed and aligned in a plane substantially parallel with the plane of the body of the shutter blades 48. In this way, when the blades 48 are opened, as illustrated in Fig. 8, the 35 40 slots 51 are then disposed substantially parallel with the path of air flow through the winterfront so that air may pass through the slots 51 with minimized restriction effect. When the shutter blades 48 are closed, the slots 51 also serve to 45 connect the overlapped slots 50 with the suction of the fan (such as the fan 23 of Fig. 1). In other words, the suction of the fan is effective at this time through the slots 50 and 51 to seal the overlapping portions of the blades 48 against 50 each other as in the first-described form. Also, 55 by locating the seal slots 50 in the beads 49, narrower shutter blades may be employed with less blade overlap, thereby tending to reduce the amount of blade material required as well as the 60 amount of space required for mounting and operating the blades. It will be understood, however, that, if desired, the slots 51 may be located in the plane body portion of the shutter blade closely adjacent to the bead 49 so that the suction of the fan is directly effective through the slots to seal 65 the shutter blades. In other respects, the shutter structure just described is similar to and operates like the structure previously described.

In some instances, I may employ a shutter 70 blade like that shown in Fig. 9. This shutter blade, which is designated by the numeral 52, is similar to that shown in Figs. 7 and 8 except that the bead 53 formed at the pivoted or swiveled edge of the blade is not completely closed, thereby 75 providing a continuous, open slot 54 along the inner side thereof. In this form, a longitudinal row of spaced slots 55 are provided in the head opposite the continuous slot 54 thereby tending to further minimize restriction to air flow through

the right-angled blade flanges 27 which are of slight height and offer a minimum restriction to air flow. To further minimize obstruction to air flow in the open position of the winterfront, the 5 free edges of the shutter blades are preferably rounded, as best shown in Fig. 6. If desired, a screen 63 of sufficient size to cover the forward part of the winterfront may be secured to the frame members 25, as shown in Fig. 3.

10 In some instances, dependent upon the length of the shutter blades and the particular material employed, it may be desirable to further strengthen the edge of the shutter blade that is connected to the frame to prevent sagging, buckling 15 or other distortion of the same. In that case, I may employ a shutter structure such as shown in Figs. 7 and 8, wherein each of the shutter blades 48 has its swiveled or pivoted edge rolled to provide a closed tubular reinforcing bead 20 49. The shutter blades 48 overlap each other, and that portion of the bead 49 of each blade which is overlapped is provided with a longitudinal series of spaced slots 50 similar to the slots 47 (Figs. 2 and 3). All of the blades 48 are pivotally supported similarly to the previously described blades 26 and their body portions are slightly offset at 48 so that the overlapping surfaces of the blades may seat flush against each other. Unless otherwise provided against, the 25 30 rolled or beaded blade edges 49 would tend to offer restriction to the flow of air through the winterfront when the shutter blades 48 are opened. To minimize such obstruction, the opposite sides of each bead 49 are provided with diametrically opposed, longitudinally extending rows of slots 51 which are disposed and aligned in a plane substantially parallel with the plane of the body of the shutter blades 48. In this way, when the blades 48 are opened, as illustrated in Fig. 8, the 35 40 slots 51 are then disposed substantially parallel with the path of air flow through the winterfront so that air may pass through the slots 51 with minimized restriction effect. When the shutter blades 48 are closed, the slots 51 also serve to 45 connect the overlapped slots 50 with the suction of the fan (such as the fan 23 of Fig. 1). In other words, the suction of the fan is effective at this time through the slots 50 and 51 to seal the overlapping portions of the blades 48 against 50 each other as in the first-described form. Also, 55 by locating the seal slots 50 in the beads 49, narrower shutter blades may be employed with less blade overlap, thereby tending to reduce the amount of blade material required as well as the 60 amount of space required for mounting and operating the blades. It will be understood, however, that, if desired, the slots 51 may be located in the plane body portion of the shutter blade closely adjacent to the bead 49 so that the suction of the fan is directly effective through the slots to seal 65 the shutter blades. In other respects, the shutter structure just described is similar to and operates like the structure previously described.

In some instances, I may employ a shutter 70 blade like that shown in Fig. 9. This shutter blade, which is designated by the numeral 52, is similar to that shown in Figs. 7 and 8 except that the bead 53 formed at the pivoted or swiveled edge of the blade is not completely closed, thereby 75 providing a continuous, open slot 54 along the inner side thereof. In this form, a longitudinal row of spaced slots 55 are provided in the head opposite the continuous slot 54 thereby tending to further minimize restriction to air flow through

the right-angled blade flanges 27 which are of slight height and offer a minimum restriction to air flow. To further minimize obstruction to air flow in the open position of the winterfront, the 5 free edges of the shutter blades are preferably rounded, as best shown in Fig. 6. If desired, a screen 63 of sufficient size to cover the forward part of the winterfront may be secured to the frame members 25, as shown in Fig. 3.

10 In some instances, dependent upon the length of the shutter blades and the particular material employed, it may be desirable to further strengthen the edge of the shutter blade that is connected to the frame to prevent sagging, buckling 15 or other distortion of the same. In that case, I may employ a shutter structure such as shown in Figs. 7 and 8, wherein each of the shutter blades 48 has its swiveled or pivoted edge rolled to provide a closed tubular reinforcing bead 20 49. The shutter blades 48 overlap each other, and that portion of the bead 49 of each blade which is overlapped is provided with a longitudinal series of spaced slots 50 similar to the slots 47 (Figs. 2 and 3). All of the blades 48 are pivotally supported similarly to the previously described blades 26 and their body portions are slightly offset at 48 so that the overlapping surfaces of the blades may seat flush against each other. Unless otherwise provided against, the 25 30 rolled or beaded blade edges 49 would tend to offer restriction to the flow of air through the winterfront when the shutter blades 48 are opened. To minimize such obstruction, the opposite sides of each bead 49 are provided with diametrically opposed, longitudinally extending rows of slots 51 which are disposed and aligned in a plane substantially parallel with the plane of the body of the shutter blades 48. In this way, when the blades 48 are opened, as illustrated in Fig. 8, the 35 40 slots 51 are then disposed substantially parallel with the path of air flow through the winterfront so that air may pass through the slots 51 with minimized restriction effect. When the shutter blades 48 are closed, the slots 51 also serve to 45 connect the overlapped slots 50 with the suction of the fan (such as the fan 23 of Fig. 1). In other words, the suction of the fan is effective at this time through the slots 50 and 51 to seal the overlapping portions of the blades 48 against 50 each other as in the first-described form. Also, 55 by locating the seal slots 50 in the beads 49, narrower shutter blades may be employed with less blade overlap, thereby tending to reduce the amount of blade material required as well as the 60 amount of space required for mounting and operating the blades. It will be understood, however, that, if desired, the slots 51 may be located in the plane body portion of the shutter blade closely adjacent to the bead 49 so that the suction of the fan is directly effective through the slots to seal 65 the shutter blades. In other respects, the shutter structure just described is similar to and operates like the structure previously described.

In some instances, I may employ a shutter 70 blade like that shown in Fig. 9. This shutter blade, which is designated by the numeral 52, is similar to that shown in Figs. 7 and 8 except that the bead 53 formed at the pivoted or swiveled edge of the blade is not completely closed, thereby 75 providing a continuous, open slot 54 along the inner side thereof. In this form, a longitudinal row of spaced slots 55 are provided in the head opposite the continuous slot 54 thereby tending to further minimize restriction to air flow through

the vehicle, with a minimum obstruction so that the full benefit of the cooling effect thereof may be utilized for temperature control purposes. The improved manner of mounting the shutter blades 5 reduces manufacturing cost, simplifies the structure as a whole, and aids generally in the accomplishment of the advantages hereinabove stated.

I claim:

1. A winterfront or the like adapted for use 10 with a radiator through which air is drawn by a fan for cooling purposes, which comprises a casing adapted to be mounted in front of the radiator, a plurality of shutter blades movable between an open and closed position and so arranged 15 that they overlap each other in closed position, and a plurality of spaced slots in the overlapped portions of said blades adapted to expose the overlapping surfaces of said blades directly to the suction created by the fan for effecting a substantially sealed contact between the surfaces of said blades which overlap each other.

2. A device of the character described which comprises a frame, a plurality of shutter blades, 25 means for mounting said blades for swing movement about one edge thereof, means by which all of said blades are simultaneously moved to similar extents between an open and a closed position, said blades being so constructed and 30 arranged that they overlap each other in closed position, the overlapped portions of said blades being provided with a longitudinally extending series of spaced slots through which the overlapping surfaces of said blades are exposed.

3. A device of the character described, which comprises a frame, a plurality of shutter blades each having one of its longitudinal edges turned over to stiffen the same, means carried by said blades along the stiffened edge thereof at the 40 opposite ends thereof only for swingably connecting said blades to said frame, means for moving all said blades to similar extent between open and closed positions, said blades being of such width and so arranged that the edge portion 45 of one blade opposite its stiffened edge overlaps the stiffened edge portion of the adjacent blade, and the overlapped of said blades each having a longitudinally extending series of slots adjacent its stiffened edge and through which 50 the overlapping blade portions are rearwardly exposed.

4. A device of the character described comprising a frame, a plurality of comparatively thin, plane-surface shutter blades disposed vertically in said frame, each of said blades having one edge thereof turned slightly out of the plane thereof to strengthen the same, swivel means connected to each said blade at the opposite ends only thereof adjacent said strengthened edge and 55 also swiveled to said frame for swingably mounting said blades for movement toward and from a closed position, said blades being of such width and so located relatively that the free edge of one blade overlaps the strengthened edge of the 60 adjacent blade, and the overlapped portion of each blade having a plurality of longitudinally extending spaced slots that are covered exteriorly by the overlapping portions of adjacent blades in the closed position of said blades.

70 5. A shutter blade for a device of the character described which includes an elongated plane-surfaced body portion, a turned-over flange along one side edge of said body portion for stiffening purposes, a short swivel member carried by said 75 body portion at each end adjacent said turned-

over flange, and said body portion being provided with a longitudinal series of slots located adjacent said turned-over flange between said swivel members.

6. A shutter blade for a device of the character described which includes an elongated plane-surfaced body portion having one longitudinal edge rolled to provide a tubular strengthening bead thereat, swivel mounting means associated with said bead at the opposite ends only of said body portion, and said bead having longitudinally spaced slots extending substantially throughout the said body portion. 5

7. A shutter blade for a device of the character described which includes an elongated plane-surfaced body portion having one longitudinal edge rolled to provide a tubular strengthening bead thereat, swivel mounting means associated with said bead at the opposite ends only of said body portion, said bead having a longitudinal series of slots extending substantially throughout the length of said body portion, and said bead having additional and diametrically opposed, longitudinally extending series of slots therein with each said additional series disposed 20 in a plane aligned substantially parallel with the plane of said body portion. 15

8. A winterfront or the like adapted for use with a radiator through which cooling air is drawn by a fan, which comprises a frame adapted 30 to be mounted in front of the radiator, a plurality of plane-surface, comparatively narrow shutter blades mounted for swivel movement in said frame, a rolled tubular bead formed along one edge of each said blade and said blades being of 35 such width and so located relatively that substantially only the beaded edge of one blade is overlapped exteriorly by a free edge of an adjacent blade in the closed position of said blades, each of said blades in the beaded edge thereof having 40 longitudinally spaced slots that are covered by the overlapping portion of the adjacent blade whereby the suction of the fan is effective through said slots to seal the engaged overlapping surfaces of said blades against each other in the 45 closed position thereof.

9. A winterfront or the like adapted for use with a radiator through which cooling air is drawn by a fan, which comprises a frame adapted 50 to be mounted in front of the radiator, a plurality of plane-surface shutter blades mounted for swivel movement in said frame, a rolled tubular bead formed along one edge of each said blade and said blades being of such width and so located relatively that the beaded edge of one blade 55 is overlapped exteriorly by a free edge of an adjacent blade in the closed position of said blades, each of said blades adjacent the beaded edge thereof having separated longitudinal series of slots, some of which are covered by the overlapping portion of the adjacent blade and others of which series are aligned and diametrically opposed and disposed in a plane substantially parallel with the plane of said blades whereby air 60 may pass therethrough in the open position of 65 said blades, and said first-mentioned series of slots are connected to the suction of the fan in the closed position of said blades.

10. A shutter blade for a device of the character described, which comprises an elongated 70 plane-surfaced body portion having one edge rolled to provide a tubular strengthening bead thereat, swivel mounting pins mounted in the opposite ends of said bead, said bead being so constructed and arranged that there are a plurality 75

of longitudinally disposed and spaced slots in the side thereof disposed substantially in the plane of said body portion, and also openings in said bead on opposite sides thereof and aligned with each other in a plane spaced from but substantially parallel with the plane of said body portion.

11. A shutter blade for a device of the character described, which comprises an elongated plane-surfaced body portion having one edge 10 rolled to provide a tubular strengthening bead thereat, swivel mounting pins mounted in the opposite ends of said bead, said bead being so constructed and arranged that there are a plurality of spaced slots in one side thereof for permitting the passage of air through the bead at substantially right angles to the plane of said body portion, and a plurality of diametrically opposed openings in other sides of said bead and extending thereto at substantially right angles to said 15 slots and in a direction substantially parallel with the plane of said body portion.

12. A device of the character described which includes a plurality of shutter blades, means secured to the opposite ends of each of said blades 20 and at a point between the side edges thereof for mounting said blades for swing movement between open and closed positions, said blades being so arranged that the forward edge portion thereof on one side of said mounting means overlaps the 25 tail edge portion on the opposite side of said mounting means of an adjacent blade, said overlapped tail edge portions being provided with a longitudinal series of spaced slots through which the overlapping surfaces of the forward blade 30 portions are rearwardly exposed.

13. A device of the character described which includes a plurality of shutter blades, means secured to the opposite ends of each of said blades 35 and at a point approximately one third of the distance between the side edges thereof for mounting said blades for swing movement between open and closed positions, said mounting means dividing each said blade into a forward and a tail portion, said blades being so arranged that the forward portion thereof overlaps the tail portion 40 of an adjacent blade, said overlapped tail portions being provided with a longitudinal series of spaced slots through which the overlapping surfaces of the forward blade portions are rearwardly exposed.

14. A shutter blade for a device of the character described, which comprises an elongated body of rectangular outline shape, swivel mounting means carried by said body along one of the side 45 edges thereof and projecting from the opposite ends thereof, said body portion being provided

with longitudinally spaced slots, the arrangement being such that when the slotted blade body is overlapped by another blade the surface of the overlapping blade is exposed through said slots.

15. A winterfront adapted for use with a cooling system that includes a fan that induces a flow of air by suction through the winterfront, which comprises a frame, a plurality of shutter blades movable between open and closed positions and so mounted that they overlap each other in closed 10 position, said blades having slots therein so arranged that portions of the overlapping surfaces of said blades are directly exposed through the overlapped blade surfaces whereby the suction of a fan located behind the winterfront effects a substantially sealed contact between the blade surfaces when the blades are in closed position.

16. A shutter blade for a device of the character described, which includes a flat body portion, a turned-over flange along one side edge of said 20 body portion for stiffening purposes, swivel means carried by said body portion and projecting therefrom at each end thereof adjacent said flange, and said body portion being provided with longitudinally spaced slots so located that they will be 25 covered by an overlapping blade when two overlapping blades are brought into overlapping relation.

17. A shutter blade for a device of the character described, which includes a flat body portion 30 having one longitudinal edge rolled to provide a tubular strengthening bead thereat, swivel means associated with said bead and extending from the opposite ends of said body portion, said bead having at least three series of spaced slots therein, 35 two of which series extend oppositely to each other in a plane substantially parallel with the plane of said body portion.

18. A device of the character described comprising a frame, a plurality of shutter blades disposed vertically in said frame, each of said blades having one edge thereof turned slightly out of the plane thereof to strengthen the same, swivel means connected to each blade and extending from the opposite ends thereof adjacent said 40 strengthened edge, said swivel means being mounted in said frame for swingably mounting said blades and for movement toward and from a closed position, said blades being of such width and so located that the free edge of one blade 45 overlaps the strengthened edge of the adjacent blade, and the portion of each blade adapted to be overlapped by an adjacent blade being slotted to expose a part of the engaging surface of the overlapping blade.

D. NORVELL GATFIELD.
